(57) **CLAIM**

The ornamental design for a mini blaster, as shown and described.

DESCRIPTION

FIG. 1 is a bottom, right and front side perspective view of a mini blaster, showing my new design;

FIG. 2 is top, left and back side perspective view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view thereof; and,

FIG. 8 is a back elevational view thereof.

The broken lines shown in the drawings represent portions of the article that form no part of the claimed design.

1 Claim, 8 Drawing Sheets
